ELECTRICAL CONDUCTOR

Ben K. Ford, Westfield, N. J., assignor to Western Electric Company, Incorporated, New York, N. Y., a corporation of New York

Original application June 28, 1938, Serial No. 216,252. Divided and this application October 24, 1939, Serial No. 300,934

3 Claims. (Cl. 174—121)

This invention relates to electrical conductors, and more particularly to insulated electrical conductors.

This application is a division of my copending application Serial No. 216,252, filed June 28, 1938, which has matured to Patent No. 2,234,671, dated March 11, 1941.

In the art of manufacturing insulated electrical conductors copper is frequently employed for the conductor and rubber is frequently employed to form an insulating sheath therefor. It has been considered important, however, that suitable materials be disposed between the conductors of copper and an insulating sheath to serve as a barrier between them to maintain the conductor clean.

An object of the invention is to provide a simple, efficient and practical insulated conductor.

With this and other objects in view, the invention comprises an insulated core having a plurality of knitted coverings jointly serving as a barrier between the core and insulated sheath formed of plastic material.

Other objects and advantages will be apparent from the following detailed description when taken in conjunction with the accompanying drawing which illustrates an insulated core embodying the invention.

In the present embodiment of the invention a core 47 is formed of a plurality of conductor strands such as copper, with the strands inter-twisted as illustrated in the drawing. A textile covering 63 is knitted on the core 47 and a textile covering 64 is knitted over the covering 63. It will be apparent, by viewing the drawing, that the courses in each covering extend longitudinally of the core, while the wales consisting of interconnected loops of successive threads extend spirally about the core in different directions.

Upon the covering 64 a sheath of soft rubber is disposed. A sheath formed of rubber provides a very flexible and weather-proof insulator for the conductor core but it is important that the conductor be kept clean and free of deposits to condition any portion thereof for soldering. For this and other reasons it is not considered advisable to place the rubber sheath directly upon the copper core. In order to provide a barrier for the rubber sheath which will not decrease the flexibility of the entire assembly but will add greatly to the tensile strength and life thereof the knitted coverings 63 and 64 are formed between the core and the sheath in opposite directions relative to the general axis of the core. These knitted coverings serve not only as a posi-

tive barrier for the sheath but permit free bending and twisting of the assembly without possibility of the strands of the core projecting therethrough and coming in contact with the rubber sheath. It will be observed that the loops of the covering 64 extend spirally in the direction of the twisting of the strands which compose the core, while the loops of the covering 63 extend in a different or opposite direction. Therefore, 5 if the assembly should be twisted in one direction, for example, the direction to untwist the strand of the core, which direction would also tend to loosen the covering 64, the covering 63 would be tightened about the core to eliminate 10 the possibility of the strands of the core from being loosened and coming in contact with a sheath 68. Furthermore, twisting of the assembly in the opposite direction would not only tighten the strands of the core but would tighten the covering 64, although such would tend to loosen the covering 63. It is, therefore, apparent that by 15 twisting the assembly in either direction in an attempt to loosen one of the coverings the other covering would be tightened about the core, preventing any of the strands from projecting 20 therethrough.

The present embodiment of the invention is, therefore, an article of manufacture which consists specifically of a copper core formed, if desired, of a plurality of copper strands covered with a sheath formed of plastic material, preferably soft rubber, and having two or more knitted coverings between the core and the sheath serving as a barrier to prevent the rubber of the 25 sheath contacting with the core during extrusion thereof or during service of the article.

The embodiment of the invention herein disclosed is illustrative only and may be modified and departed from in many ways without departing from the spirit and scope of the invention as 30 pointed out in and limited only by the appended claims.

What is claimed is:

1. An electrical conductor comprising an electrical conductor core, a plastic sheath disposed thereon, and knitted coverings with wale portions and course portions disposed one upon another on the core between the core and the sheath and serving as a barrier therebetween, the course portions of the coverings extending longitudinally of the core and the wale portions extending spirally about the core in opposite directions.

2. An electrical conductor comprising an electrical conductor core, a knitted covering disposed 50 on the core with wales of the covering extending

spirally about the core in one direction, a second knitted covering disposed on the first knitted covering with the wales of the first knitted covering extending spirally about the core in a different direction, and a sheath of plastic material formed over the covered core and completely separated from the core by the coverings.

3. An electrical conductor comprising an electrical conductor core, a knitted covering disposed on the core with wales of the covering extending 10 spirally about the core in one direction, a second

knitted covering disposed on the first knitted covering with the wales of the first knitted covering extending spirally about the core in a different direction, each covering being formed of interconnected loops to be closed over the core when the core is twisted to loosen the loops of the other covering, and a sheath of plastic material formed over the covered core and completely separated from the core by the coverings.

BEN K. FORD.
